UNITED STATES PATENT OFFICE.

OTTO PETERMANN, OF GROTON, NEW YORK, ASSIGNOR TO STANDARD TYPEWRITER COMPANY, A CORPORATION OF NEW YORK.

TYPE-WRITING-MACHINE CONSTRUCTION.

1,062,027.

Specification of Letters Patent.

Patented May 20, 1913.

Application filed September 15, 1910. Serial No. 582,214.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing-Machine Constructions, of which the following is a full, clear, and exact description.

10 This invention relates more particularly to the construction of the frame and carriage of typewriting machines in which the carriage is adapted to be shifted or moved into compact relation to another part of the 15 typewriter.

One object of the invention is to provide a frame and carriage which may be stamped or formed from sheet steel or other metal in such a way as to be strong, light and attractive in appearance, and which frame may be so made that it is adapted to have certain parts of the mechanism held thereto, thereby providing a machine which may be easily assembled without the necessity of 25 attaching separate parts to the frame and at the same time materially reducing the cost of manufacture.

Other objects of the invention are to provide a simple and easily constructed frame 30 in which approximately the entire frame is made of a single piece of sheet metal and in which only the transverse or bracing bars are made independent thereof; to provide simple and efficient transverse bars and 35 means for attaching the same to the sides of the machine frame; and to provide the frame with means whereby the type-bars may be properly supported on a part thereof.

40 A further object of the invention is to provide means whereby the frame may be constructed to form a supporting and guiding means for a part of the platen-shift mechanism, and as a means to support a 45 part of the escapement mechanism.

With these and other objects in view, the invention will be hereinafter more particularly described with reference to the accompanying drawings, which form a part 50 of this specification, and will then be pointed out in the claims at the end of the description.

In the drawings, Figure 1 is a longitudinal section, partly in elevation, of one form 55 of machine embodying my invention. Fig.

1^a is a fragmentary view, showing how one of the transverse bars may be attached to the sides of the frame. Fig. 2 is a detail side elevation of the frame. Fig. 3 is a longitudinal section of the frame. Fig. 4 is a rear elevation of the frame. Fig. 5 is a detail plan view of the frame. Fig. 6 is a fragmentary perspective view of one of the rear corners of the frame serving as guides for the shift bars. Fig. 7 is a fragmentary perspective view of one of the front corners of the frame with the transversely-extending brace bar; and Fig. 8 is a fragmentary perspective view, showing the form of transverse bar serving as pivoting and guiding means for the space-bar levers and as attaching means for the springs connected to the key-levers.

While I show the invention as applied more particularly to a type of machine in which the carriage and bed are folded over into overhanging relation to the keyboards, it will be understood that the invention may be applied to other forms of typewriting machines and may be constructed to adapt it for such purpose without departing from the nature of the invention.

The machine may be provided with any suitable mechanism. As shown, a plurality of transversely-extending rods 10 are arranged between the sides of the frame, and suspended on these rods are the key-levers 11, the inner ends of which are connected by links 12 to the type-bars 13. These type-bars have heads 14 on which may be arranged a plurality of characters indicating the upper and lower case type or the figures or other characters as is usual in typewriting machines. Arranged above the frame is a support 15 which is adapted to be elevated and mounted on the support is a bed 16 on which is adapted to move a carriage 17, and on said carriage 17 is supported the platen 18. The support 15 may be foldable or arranged in any other desired way, and said support may be carried by the bars or slides 19, the lower ends of which are adapted to be operatively connected to one or more shift levers 20. Only one shift lever is shown and this is pivotally held to a transverse rod 21 so that when said shift lever is moved on its pivot, the support 15 and the carriage and bed may be elevated the desired extent. The parts thus far described, with the exception of the frame and 110

the carriage and bed, may be of any suitable or preferred construction.

To support the working parts of the machine and to make the frame light and at the same time very strong, and to provide a serviceable machine as well as one particularly adapted to be transported easily, I provide a frame 22 in which the sides 23 and rear part 24 are made of a single piece of sheet metal. As shown, the frame at the rear portion 24 is provided with two grooved portions 25 and 26 forming two curved inwardly-extending ribs 27, and these ribs are each provided with apertures 28 which are stamped by means of dies or otherwise formed, and which serve as means through which screws 29 may pass to engage the base of brackets 30, the latter forming pivotal and supporting means for the type-bars 13. The frame is provided with a flange 31 along its upper edge and with a flange 32 along its lower edge, both of which flanges are inturned. The upper flange is rounded for a part of its length and said flanges as well as the ribs 27 serve as strengthening means and at the same time the flanges give a substantial appearance to the frame.

At each corner of the frame and at the rear thereof are two integral extensions or parts 33 and 34, the former of which projects inward from one of the sides 23 of the frame, and the extension 33 from the rear part 24 of the frame. These parts overlap and each have an opening 35 stamped or formed therein, and fitting these openings at each side thereof is a bushing or thimble 36 serving as a rivet to hold the two extensions at each corner together and as a guiding means for one of the vertically movable bars 19 of the shift mechanism. The lower rear corners of the frame, Figs. 1 and 6, have extensions or lugs 35^a and 36^a, and these lugs overlap and project from the lower flange 32 and are riveted or otherwise held together, thus strengthening the frame at this point. By providing the overlapping extensions at the corners to serve as guiding means for the shift bars or rods, the ribs at the rear of the frame, and making said ribs and extensions integral with the flanged sheet metal frame, a very simple and effective construction is provided.

The frame has its side members 23 joined together at the front portion thereof by a transversely-extending bar 37. This bar is substantially C-shaped in cross-section by reason of its inturned flanges at the upper and lower portion thereof. The bar 37 has its lower flange extended at two points, as at 37^a, and these points are adapted to limit the downward movement of the spacing bar 37^b, the latter having a bracket or brackets 37^c secured thereto or other means provided which is adapted to engage said extensions

37^a when the bar 37^b is depressed, said spacing bar having levers 37^d which are supported in any suitable manner to operate the universal bar of the escapement mechanism. The transverse bar has its ends provided with lugs or projections 38 which fit over an integral projection 39 forming a part of the lower flange 32 of each side member, the said lugs 38 and 39 of the frame and the transverse bar 37 being riveted or otherwise held, as desired. The transverse bar 37 may be provided with flanges 40 at its ends serving as further means to securely hold said front piece or bar 37 to the side members. The frame is provided with a curved portion 41 extending downward from substantially the central portion thereof, and this curved portion terminates in a concaved portion 42 located above the transversely-extending bar 37. This concaved portion 42 serves as a seat or rest for the platen 18, shown in dotted lines in Fig. 1, when the platen and carriage are folded into compact relation with respect to the keyboard. An intermediate bar 44, also of sheet metal, extends transversely of the machine, between the rear part 24 and the front piece 37, and the flange 31 is cut away to provide two slots 45 and 46 into which tongues projecting from the ends of the bar 44 are adapted to fit, and which hold the bar properly between the said side members. The transverse bar may be provided with other fastening means, if desired, but ordinarily the slots 45 and 46 serve to properly hold the bar in position. Both bars 37 and 44 may be of any suitable shape, and instead of making the frame curved at its upper edge between the bar 44 and the rear part 24, it may be made straight and the part 42 may be also straight instead of concaved.

A bar 47 is located intermediate the rear and front portion of the machine and is secured to the lower flanges 32 of the sides of the frame. The bar is angular in form and has a flange 48 provided with a plurality of apertures 49 to which one end of each spring 50 may be attached, the other end of said spring being attached to one of the key-levers. The bar 47 is provided with an integral guiding portion 51 extending upwardly therefrom and this guiding portion has two side flanges 52 and a slotted portion 53, Fig. 8, which serves as a pivot for the space-bar levers 37^b, the said levers being guided in the slots and being notched to fit over a portion of the bar 47 so as to form substantially a knife-edged pivot therefor.

At the rear part of the frame, the lower flange 32 is formed with an extended portion which is bent downward, as at 54, and is provided with an aperture through which passes a bolt 55. This bolt 55 is provided with a nut 56 at one end and its other end

is attached to one end of a spring 57, the other end of said spring being held to the arm 58 extending from the transverse rod 21, said spring acting as a tension means tending normally to raise the inner end of the shift lever 20 and carriage to partly compensate for the weight of the carriage and parts shiftable therewith. The extensions or parts 33 are each provided with a downwardly-extending portion 59. The portions 59 each have an aperture 60, which may be formed by dies or otherwise, and said portions serve as supports to which are pivoted bell-crank levers 60^a forming a part of an escapement mechanism. Each bell-crank lever has one end thereof operatively connected to rock arms 60^b forming a part of an escapement frame. This frame has a transverse bar which is adapted when moved to operate suitable means, as a lever 60^c, which is connected to the escapement dogs. The other end of each bell-crank lever is pivotally connected to a part projecting upward from the universal bar 60^e, the latter being operated by the key-levers and the spacing bar as is usual in typewriting machines. This mechanism is not claimed herein as it is substantially the same as disclosed in my pending application Serial No. 603,122, filed Jan. 17, 1911. The machine frame as thus constructed comprises very few parts and not only is the frame strong and light, but the said frame may be made of sheet steel or other metal and may have some of the working parts of the machine directly supported thereby.

The frame of the machine is supported on rubber feet or cushions 61 which are held in caps 62, these caps being separate from the frame or formed as a part thereof, it being understood that the caps at the front of the frame may be formed as a part of the transversely extending bar 37 or separate therefrom.

In the present invention substantially the entire frame may be made of a single piece of metal thus making the machine very light and strong and at the same time inexpensive to manufacture which is very important in machines of this character.

While this application discloses other features of a typewriting machine than those claimed herein, such features including the carriage construction, the universal bar mechanism and other parts, are covered by applications already filed or to be filed.

In the present invention, the machine frame and carriage bed and carriage frame form the essential features of the invention, and by the construction shown, substantially the entire frame may be made of a single piece of metal, and the same is true of the carriage bed and the carriage frame, thus making the machine very light and strong and at the same time inexpensive to manu-

facture which is very important in machines of this character.

Having thus described my invention, I claim as new and desire to secure by Letters Patent:—

1. In a typewriting machine, a frame having its rear portion and sides formed of a single piece of sheet metal, the upper and lower edges of which are provided with inwardly-extending flanges to adapt the same to be made light and strong, integral means located at the rear corners for holding the sides at substantially right angles to the rear portion, and a transversely-extending and substantially C-shaped bar at the forward part of said frame connecting the sides together. 70 75 80

2. In a typewriting machine, a substantially rectangular frame having its rear portion and sides formed of a single piece of sheet metal and provided with flanges to adapt the same to be made light and strong, means connecting the sides together, and overlapping integral corner pieces for holding the frame in shape. 85 90

3. In a typewriting machine, a frame having its rear portion and sides formed of a single piece of sheet steel, the upper and lower edges of which are provided with inwardly-extending flanges to adapt the same to be made light and strong, and means located at the rear corners for holding the frame in shape. 95 100

4. In a typewriting machine, a frame having its rear portion and sides formed of a single piece of sheet metal, the upper and lower edges of which are provided with inwardly-extending flanges to adapt the same to be made light and strong, said sides and rear portion having inwardly-extending parts at the corners projecting from the flanges, each part having an opening therethrough and together serving as guiding means, platen shift mechanism having a part movable in said guiding means, and a transversely-extending bar at the forward part of said frame connecting the sides together. 105 110 115

5. In a typewriting machine, a frame formed of sheet metal and having inwardly-extending overlapping portions at the rear corners, said overlapping portions having openings therein, and platen shift mechanism having a part thereof passing through said openings. 120 125

6. In a typewriting machine, a frame formed of sheet steel and having inwardly-extending flanges and overlapping projecting portions at the rear corners, and means guided by said overlapping portions. 125

7. In a typewriting machine, the combination with a platen, of bars connected to move with the platen in one direction, mechanism for shifting the bars and platen, and a frame formed of sheet metal having 130

- inwardly-projecting integral means at the rear corners provided with openings, and thimbles held in said openings forming guides for the bars. 65
5. 8. In a typewriting machine, a frame formed of sheet metal having inturned flanges and having inwardly-projecting integral parts at the rear corners thereof, said parts having openings, thimbles held in said 70 openings, and platen shift mechanism having a part thereof movable in the thimbles.
10. 9. In a typewriting machine, a frame made of sheet metal and provided with inwardly-extending flanges at the upper and lower portions thereof and having parts 75 projecting from the upper flange at the rear corners of the frame, said parts extending downwardly and provided with openings, and means forming a part of an escapement mechanism pivotally held in 15 said openings.
15. 10. In a typewriting machine, a frame made of sheet steel and provided with parts projecting from the upper part of the frame 80 and at the rear corners thereof, said parts having downwardly-extending portions, and means forming a part of an escapement mechanism held to said portions.
20. 11. In a typewriting machine, a frame made of sheet metal and provided with inwardly-extending flanges at the upper and lower portions thereof and having parts 85 projecting from the upper flange at the rear corners of the frame, said parts serving as guiding means and having downwardly-extending portions, and means forming a part of an escapement mechanism held to said portions. 90
25. 12. In a typewriting machine, a frame having its sides and rear portion formed of a single piece of sheet metal, and having flanges at the upper and lower portions thereof, said rear portion being depressed to provide transversely-extending ribs and 95 having openings in said ribs, and type-bar brackets supported by said ribs.
30. 13. In a typewriting machine, a frame having its sides and rear portion formed of a single piece of sheet metal, said rear portion being pressed inwardly to provide 100 transversely curved ribs and having openings in said ribs, type-bar supporting means, and means for holding said supporting means to the ribs.
35. 14. In a typewriting machine, a frame having its sides and rear portion formed of a single piece of sheet metal and having inturned flanges, said rear portion being pressed inwardly to provide transverse 105 ribs, and type-bar supporting means held to said ribs. 110
40. 15. In a typewriting machine, a frame having its sides and rear portion formed of a single piece of sheet metal provided with inturned flanges at the upper and lower portions thereof, and having an integral portion extending downwardly therefrom, a carriage, and tension means connected to said portion tending normally to force the carriage upward. 115
45. 16. In a typewriting machine, a frame having its sides and rear portion formed of a single piece of sheet metal provided with inturned flanges and having an integral portion extending downwardly therefrom at the rear and lower part thereof, a carriage, and tension means connected to said portion and tending normally to force the carriage upward. 120
50. 17. In a typewriting machine, a frame having its sides and rear portion formed of a single piece of sheet metal, and having inturned flanges at its upper and lower surfaces, said frame having the forward portion of the sides thereof concaved, a platen, and means whereby the platen may be shifted to rest in said concaved portion. 125
55. 18. In a typewriting machine, a frame having its sides and rear portion formed of a single piece of sheet metal, and having inturned edges, said frame having the forward portion of the sides thereof concaved, a platen, and means whereby the platen may be folded forward to rest in said concaved portion. 95
60. 19. In a typewriting machine, a frame having its rear and side walls formed of a single piece of sheet metal and provided with inturned flanges at the upper and lower portions thereof, a spacing bar, and frame bars extending transversely thereof between the sides, one of said bars having inturned flanges and provided with lugs fitting over and secured to the lower inturned flanges of the side walls, and having inwardly-projecting parts serving to limit the downward movement of the spacing bar. 100
65. 20. In a typewriting machine, a frame having its rear and side walls formed of a single piece of sheet metal and provided with inturned flanges at the upper and lower portions thereof, and bars extending transversely thereof between the sides, one of said bars having inturned flanges and provided with lugs fitting over and secured to the lower inturned flanges of the side walls. 110
70. 21. In a typewriting machine, a frame having its rear and side walls formed of a single piece of sheet metal and provided with inturned flanges at the upper and lower portions thereof, and a bar having inturned flanges and provided with lugs fitting over and secured to the lower inturned flanges of the side walls. 115
75. 22. In a typewriting machine, a frame made of sheet metal and having its side walls provided with slots, and a transversely-

- extending curved bar having inturned flanges and tongues at its ends adapted to fit in said slots.
23. In a typewriting machine, a frame 5 having its rear and side walls made of a single piece of sheet metal and provided with inturned flanges at the upper and lower portions thereof, space-bar levers, key lever springs, a transversely-extending bar secured to the lower flanges between the side walls and having means for fastening the key-lever springs thereto, and provided with upwardly-projecting substantially U-shaped guiding means serving as pivoting and guiding supports for the space-bar levers.
24. In a typewriting machine, a frame, space-bar levers, key lever springs, and a transversely-extending bar secured to the lower part of the frame between the side walls and having means for fastening the key-lever springs thereto, and provided with upwardly-projecting substantially U-shaped guiding means serving as pivoting and guiding supports for the space-bar levers.
25. In a typewriting machine, space-bar levers, a frame having rear and side walls, and a transversely-extending bar secured to the lower part of the frame between the side walls and having upwardly-projecting guiding means serving as pivoting and guiding supports for the space-bar levers.
26. In a typewriting machine, a frame having inwardly-projecting overlapping parts at the rear corners thereof, said parts having openings, and thimbles held in said openings forming guides and serving to hold said projecting parts together, and platen shift mechanism having a part there-40 of guided in said thimbles.
27. In a typewriting machine, a substantially rectangular frame formed of a single piece of sheet metal and having inwardly extending and integral overlapping portions 45 at the rear corners, and a cushioning button at each rear corner.
28. In a typewriting machine a substantially rectangular frame formed of a single piece of sheet metal and having inwardly 50 extending and integral overlapping portions at the rear corners, a cushioning button at each rear corner, and means for fastening said buttons to the overlapping portions and holding the latter together.
29. In a typewriting machine, a frame 55 formed of a single piece of sheet metal, and having integral inwardly extending overlapping portions at the rear corners to strengthen said corners and hold the frame in shape, said frame having projecting parts 60 at the forward portions thereof, a transversely extending bar having parts to overlap the extending portions at the front of the frame, cushioning buttons arranged at the rear and front corners of the frame, and 65 means for holding the buttons at the rear and front overlapping portions and serving as means for holding said overlapping portions rigidly together.
30. In a typewriting machine, a frame 70 formed of a single piece of sheet metal and having integral projecting parts at the forward portion thereof, a transversely extending bar having parts to overlap the extending portions at the front of the frame, cushioning buttons arranged at the front corners of the frame, and means for holding the buttons to the front overlapping portions and serving as a means for holding said overlapping portions rigidly together. 75
31. In a typewriting machine, a frame formed of a single piece of sheet metal and having integral inwardly extending overlapping portions at the rear corners to strengthen said corners and hold the frame in shape, 80 said frame having projecting parts at the forward portions thereof, a transversely extending bar having parts to overlap the extending portions at the front of the frame, cushioning buttons arranged at the rear and front corners of the frame, and means for supporting the buttons to the rear and front overlapping portions, said means also serving to hold said overlapping portions rigidly together. 85
32. In a typewriting machine, a frame made of sheet metal and having its side walls provided with slots, and a transversely extending bar having inturned flanges and tongues at its ends adapted to fit in said 90 slots.

This specification signed and witnessed this 12th day of September A. D. 1910.
